UNITED STATES PATENT OFFICE

124,754

DESIGN FOR A MERCHANTISE DISPLAY CASE

José Trojan, Chicago, Ill., assignor to Owen Housholder and David C. Cohen, co-partners, doing business as Crystal Manufacturing Co., Chicago, Ill.

Application November 25, 1940, Serial No. 96,788

Term of patent 3½ years

To all whom it may concern:

Be it known that I, José Trojan, a citizen of the United States, residing at Chicago, in the county of Cook and State of Illinois, have invented a new, original, and ornamental Design for a Merchandise Display Case, of which the following is a specification, reference being had to the accompanying drawing, forming part thereof.

I claim:

The ornamental design for a merchandise display case, substantially as shown.

JOSÉ TROJAN.
